PADLOCK

James I. Seay, Jr., Memphis, Tenn.

Application February 10, 1941, Serial No. 378,159

4 Claims. (Cl. 70—38)

This invention relates to improvements in padlocks, and particularly to a body and shackle type padlock of key operated type, in which the shackle is constrained to automatically open when unlocked, and in which the key opening is transverse to the line of unlocking movement.

The objects of the invention are:

Primarily to provide a locking device which is difficult of operation with other than the complementary key.

To provide a body of laminated type which lends itself to simplification of assembly and construction and tends to reduction in cost; and

To provide a padlock having a key entrance at right angles to the axis of its assembling movement.

The means by which the foregoing and other objects are accomplished and the manner of their accomplishment will readily be understood from the following specification upon reference to the accompanying drawing, in which:

Fig. 1 is a vertical sectional elevation of the lock taken on the line I—I of Fig. 2.

Fig. 2 is a sectional plan taken on the line II—II of Fig. 1; and

Fig. 3 a similar plan taken on the line III—III of Fig. 1, with the key inserted and in initial position prior to unlocking movement.

Fig. 4 is a side elevation of the lock on a smaller scale.

Referring now to the drawing in which the various parts are indicated by numerals:

11 refers generally to the body of the lock which is made up of a plurality of plates or laminae 11—A, 11—B, etc. 13 is the shackle which has the usual long and short leg and is slidable in the direction of length of the legs toward and away from the body in suitable holes 15, 16 in the body.

Secured on the longer leg of the shackle adjacent its lower end is a collar 17 which is underlain by a compression spring 19 adapted to force the shackle outward and move the shorter leg outward to clear the top of the lock body, the collar 17 being slidable in an enlarged portion or bore 15—A of the hole 15 and movement of the collar being limited by the length of this enlarged bore to prevent dislodgement of the shackle from the body.

The two legs of the shackle are provided with oppositely disposed notches adapted, when the shackle is closed, to respectively receive locking bolts 21 and 22 which are slidably disposed in complementary openings in the laminae 11—B, 11—C and 11—D, and are respectively connected

by pins 23, 24 with links 25, 26 and these links in turn are connected by pins 27, 28 with oppositely extending portions of an arm member 29. The arm member 29 is centrally apertured to embrace, and is disposed around and constrained to turn with, a post 31 which is suitably journaled in a central vertical opening formed in certain of the laminae as the laminae 11—E, 11—F, 11—G, and 11—H. The post preferably has longitudinal grooves 31—A and the member 29 complementary integral lugs 29—A engaging these grooves. Two grooves and lugs are shown, but only one of each need be used. Springs are used to return the bolts 21 and 22 to locking position, these springs being here shown as compression springs 32 which are interposed between the ends of the links 25, 26 and abutments formed in the lamina 11—C.

Rigidly secured on the post 31 is a plate 35 carrying a plurality of depending pins 37 which are spaced at varying distances from the post and are rigidly secured in the plate. The plate underlies one of the laminae as the lamina 11—H, this lamina preventing upward movement of the plate and of the post to which it is secured.

The plate may be of circular form and is preferably provided with integral lugs conforming to the lugs 29—A of the member 29 and engageable with the grooves 31—A of the post 31 to insure proper positioning of the plate with reference to the post in addition to the other means necessary for rigidly securing it to the post. Lamina 11—J, underlying lamina 11—H, is circularly apertured to receive the plate 35. Underlying the lamina 11—J, are laminae 11—K and 11—L, having identical central circular openings slightly smaller than the plate 35, the edge of the lamina 11—K around its opening, underlying the periphery of the plate and preventing downward movement thereof. The plate 35 is of slightly less thickness than the lamina 11—J in order that the plate may be freely turned in the annular groove provided by the just mentioned assembly of laminae.

39 is a guard plate, centrally apertured to slidably embrace the post 31, and having holes conforming in number and spacing to the pins 37, the holes being of size to loosely and slidably embrace the pins. The guard 39 may be provided with lugs conforming to the lugs 29—A and engageable with the grooves 31—A of the post, or otherwise, as desired. The guard 39 may be circular if desired, or of other shape, being indicated as circular, in Fig. 3, about one-half being broken away in order that the underlying

key may better be shown. The diameter and thickness of the circular guard, or the greatest diameter otherwise, is such that the guard may be readily turned in the openings in the laminae 11-K and 11-L, and be moved freely upward or downward in such openings.

The guard 39 is supported by an underlying lamina 11-M, having a cut-away portion, as shown in Fig. 3, which comprises a semi-circular portion concentric with the post 31 and a portion extending laterally to the outer edge of the plate to provide a slot or opening 40 for insertion of a key 41. The diameter of the semi-circular portion of the opening is slightly less than the diameter of the guard 39 in order that the lamina around the semi-circular hole may underlie the peripheral edge of the guard 39 and support same against dislodgement from the post 31 and the pins 37.

The lamina 11-L, in addition to the circular central opening, is also slotted, as shown in Fig. 3, to provide a shift slot 42 for the key.

The key 41 preferably has an arcuate end conforming in radius to the semi-circular portion of the opening in lamina 11-M, so that the key in insertion may be centered and positioned. The key is provided with a central opening to receive the post, and also is provided with openings conforming in spacing and size to the pins 37 which depend from the plate 35.

The laminae preferably are secured together by rivets 43, but may be otherwise secured as by welding or brazing if desired.

In assembling, the bottom lamina 11-H, and the laminae 11-M, 11-L and 11-K are assembled as in a jig and the guard placed in the opening in the laminae 11-L and 11-K, and supported by the lamina 11-M. The lamina 11-J is placed, and the post 31 and attached plate 35 and assembly are placed with the depending pins entered in the holes of the guard 39 and the plate 35 supported by lamina 11-J and centered by lamina 11-H. Laminae 11-G and 11-F are then placed, lamina 11-G confining the plate against upward movement. The shackle spring 19 is dropped into the enlarged bore 15-A and the long leg of the shackle 17 also inserted in the bore and spring. Laminae 11-D and 11-C are now threaded on the shackle and successively placed. The arm member 29 of the locking bolt assembly is placed over and slid to position on the post 31 with the bolts 21 and 22 in their respective lamina grooves, the springs 32 are disposed in the openings, or cut-outs, made therefor in lamina 11-C, the lamina 11-D underlying the springs. Laminae 11-B and 11-A are then threaded on the shackle and moved into position, lamina 11-B overlying the springs 32 and completing the sides of the guides for the locking bolts and lamina 11-A overlying the post and the bolts. The laminae are then secured together and into a unitary structure by the rivets 43.

In use the lock is fastened by pushing the shackle into place in usual manner, the springs 32 moving the bolts 21, 22 to locking position.

To unlock, the key 41 is laterally inserted in the slot 40 of lamina 11-M and moved inward till it seats. The key is then lifted raising the guard 39 and engaging the pins 37 and the post 31 and is then shifted about the post as a center, through the pins 37 turning the plate 35 and post, and through the post to which the plate is fastened, turning the arm member 29 to shift the links 25, 26, retract the bolts and release the shackle

13 which is then shifted to open position by the spring 19.

It will be understood that the pin positioning, and if desired, pattern is varied from lock to lock 5 and the key openings correspondingly positioned and patterned.

It will further be understood that the guard is here shown as acting solely by gravity, but that a spring or springs may be interposed between it 10 and the overlying lamina if desired, though such springs are not here shown.

I claim:

1. A padlock, comprising a case having two shackle sockets, a shackle with its legs received in 15 said sockets, each of said legs having a locking notch, means biased for locking engagement with said notches, and key operable means for effecting disengagement of said locking means from said notches, said case having a centrally disposed bore extending parallel with said sockets and closed at its ends, said locking and unlocking means including a post turnably mounted in said bore, and operably connected to said notch engagement means, a plate rigidly secured on said 20 post and carrying a plurality of depending pins, a guard apertured to receive said pins and normally spaced from said plate to render end portions of said pins inaccessible, said guard being shiftable toward said plate to permit access to 25 said pins, means preventing shifting of said plate and post axially along said bore, means limiting separation of said guard from said plate, and a key having openings complementary to said pins and their spacing, said casing being apertured 30 transversely of said bore and below the level of said guard for insertion of said key, and slotted above said opening to permit shifting movement of said key axially of said bore to displace said guard and effect pin engagement, and to permit 35 subsequent turning movement of said key about said post axis to effect post turning and unlocking shift of said notch engaging means.

2. A padlock, comprising a case having two shackle sockets, a shackle with its legs received in 40 said sockets, each of said legs having a locking notch, means biased for locking engagement with said notches, and key operable means for effecting disengagement of said locking means from said notches; said case being formed from 45 a plurality of laminae disposed substantially at right angles to said sockets, and secured together as by rivets, and having a centrally disposed bore extending parallel with said sockets and closed at its ends by laminae, said unlocking means including a post turnably mounted in said bore, a plate slightly under lamina thickness rigidly secured on said post and carrying a plurality of 50 depending pins, a guard of substantially lamina thickness and smaller than said plate apertured to receive said pins and movably spaced from said plate to render end portions of said pins inaccessible, said guard being shiftable toward said plate to permit access to said pins, an intermediate said lamina being circularly apertured around said post to turnably nest said plate, the next underlying pair of laminae being 55 concentrically apertured to slidably and rotatably house said guard and underlie edge portions of said plate, the overlying and said underlying laminae preventing axial motion of said plate and post, and a fourth said lamina underlying said guard and limiting separation of said guard from said plate, and a key of slightly less than 60 lamina thickness having openings complementary to said pins and their spacing, said fourth 65 lamina being circularly apertured around said post to turnably nest said plate, the next underlying pair of laminae being concentrically apertured to slidably and rotatably house said guard and underlie edge portions of said plate, the overlying and said underlying laminae preventing axial motion of said plate and post, and a fourth said lamina underlying said guard and limiting separation of said guard from said plate, and a key of slightly less than 70 lamina thickness having openings complementary to said pins and their spacing, said fourth 75 lamina being circularly apertured around said post to turnably nest said plate, the next underlying pair of laminae being concentrically apertured to slidably and rotatably house said guard and underlie edge portions of said plate, the overlying and said underlying laminae preventing axial motion of said plate and post, and a fourth said lamina underlying said guard and limiting separation of said guard from said plate, and a key of slightly less than lamina thickness having openings complementary to said pins and their spacing, said fourth

lamina being slotted for insertion of said key, and the lower of said pair of laminae being slotted to permit movement of said key axially of said bore to displace said guard and effect pin engagement, and chambered to permit subsequent turning movement of said key about said post axis to effect post turning and unlocking shift of said notch engaging means.

3. A padlock, comprising a case having two shackle sockets, a shackle with its legs received in said sockets, at least one of said legs having a locking notch, means biased for locking engagement with said notch, and key operable means for effecting disengagement of said locking means from said notches, said case being formed from a plurality of laminae secured together as by rivets, and having a centrally disposed bore extending parallel with said sockets and closed at its ends by laminae, said locking and unlocking means including a post turnably mounted in said bore, and abutting the overlying said bore closing lamina, a plate slightly under lamina thickness rigidly secured on said post and carrying a plurality of depending pins, a guard of substantially lamina thickness and smaller than said plate apertured to receive said pins and movably spaced from said plate to render end portions of said pins inaccessible, said guard being shiftable toward said plate to permit access to said pins, an intermediate said lamina being centrally apertured to turnably nest said plate, the underlying pair of said laminae being centrally apertured to slidably and rotatably house said guard and underlie edge portions of said plate, preventing downward axial motion of said plate and post, and a fourth said lamina underlying said guard and limiting separation of said guard from said plate; and a key of slightly less than lamina thickness having openings complementary to said pins and their spacing, said post terminating above said fourth lamina and said

lamina being slotted for insertion of said key, the lower lamina of said pair of laminae being slotted and chambered to permit movement of said key axially of said bore to displace said guard and effect pin engagement, and to permit subsequent turning movement of said key about said post axis to effect post turning and unlocking shift of said notch engaging means.

4. A padlock, comprising a case having two shackle sockets, a shackle with its legs received in said sockets, at least one of said legs having a locking notch, means biased for locking engagement with said notch, and key operable means for effecting disengagement of said locking means from said notch, said case having a centrally disposed bore extending parallel with said sockets and closed at its ends, said locking and unlocking means including a post turnably mounted in said bore, a plate rigidly secured on said post and carrying a plurality of depending pins, a guard apertured to receive said pins and movably spaced from said plate to render end portions of said pins inaccessible, said guard being shiftable toward said plate to permit access to said pins, means forming part of said case preventing shifting of said plate and post axially along said bore, means limiting separation of said guard from said plate, and a key having openings complementary to said pins and their spacing, said casing being apertured transversely to said bore and below the level of said guard and the end of said post for insertion of said key, and slotted and chambered above said opening to permit shifting movement of said key axially upward of said bore to raise said guard and effect pin engagement, and to permit subsequent turning movement of said key about said post axis to effect post turning and through said post unlocking shift of said notch engaging means.

JAMES I. SEAY, JR.
